REFRIGERATOR-CABINET DEFROSTING

Glenn Muffly, Springfield, Ohio

Application August 9, 1947, Serial No. 767,731

23 Claims. (Cl. 62—116)

1

This invention has to do with refrigerated display cases, particularly of the type designed for packaged frozen foods.

The recent growth of the frozen food industry and particularly in the sale of packaged frozen foods through retail stores has created a demand for an improved type of frozen food cabinet. There is a preference for the open type of cabinet which allows the customer to see the product and to remove the desired packages without having to open a door. This is particularly important in the self-service type of store but certain disadvantages have been encountered in the use of such cabinets.

One serious difficulty is in properly defrosting the evaporators without damaging the frozen food stored in the cabinet either by allowing it to partially thaw or by allowing defrost water to contact the packages and freeze on them or freeze packages together. One defrosting method commonly employed is to scrape the frost from the cooling surfaces, but this is difficult to do without removing the frozen food packages from the cabinet and hence the defrosting operation is often neglected or improperly done. When an attempt is made to do a more thorough defrosting job, there is a serious problem in caring for the packages of frozen food which are temporarily removed from the cabinet during the defrosting operation.

Another difficulty of the open display type of frozen food cabinet is that customers are inclined to disarrange the packages in an attempt to select one which has been stored at a lower level and presents a cleaner, harder-frozen appearance. This often results in packages being stacked up to too high a level so that the upper ones start to thaw. Even after an attendant rearranges the stock these packages which have started to thaw are less salable and must often be disposed of at a loss.

One object of this invention is to provide a cabinet in which one package of each variety is visible to the customer and when removed is automatically replaced by a similar package.

Another object is to provide for magazine feed of packages to the delivery opening and for filling the cabinet through another opening.

An additional object is to insure that packages which have been in the cabinet for the longest period of time will be delivered first.

A still further object is to provide means for defrosting the evaporator which cools the cabinet without defrosting the product stored in the cabinet and without allowing drip water to fall upon the packages of frozen product.

2

A further object is to provide a pair of mirrors arranged for double reflection of the images of the packages visible in the delivery space, such images being visible to the customer with the labels directly readable because of the double reflection.

Still another object is to provide a door for closing the access opening during hours when the store is not open to customers.

10 A further object is to provide step and running board means for convenience in filling the cabinet from the top and to assure that the access opening is closed at the time the upper door through which new packages are inserted is open.

15 Still another object is to provide for rapid defrosting of the evaporator by means of a secondary circuit which causes refrigerant vapor to condense in the evaporator.

20 A still further object is to provide for automatic actuation of the defrosting means during each period when the cabinet is being restocked.

An additional object is to provide for catching the drip water during the defrosting period and conveying it to a receptacle from which it is later evaporated by means of heat dissipated by the condensing unit of the refrigerating system.

In the drawings:

Figure 1 is a vertical sectional view of the cabinet from its right-hand end.

Figure 2 is a somewhat enlarged sectional view of a portion of the top door and evaporator in the position assumed when the door is open, showing the method of draining drip water from the evaporator while it is being defrosted.

Figure 3 is a diagram of the electrical circuits for operation of the condensing unit and for energizing the defrosting means.

Figure 4 is a sectional view of the top door in its open position on the order of Figure 2 but taken in a different plane to show the refrigerant circuit and one type of heating means employed during the defrosting period.

Figures 4A and 4B are fragmentary enlarged views of certain of the elements shown in Figs. 1 and 4.

45 Figure 5 is a detail fractional view of the cabinet showing the top of the front wall and a portion of the top door to illustrate details of the door liner, breaker strip and door gaskets.

50 Figure 6 is a diagrammatic illustration of a modification in which the direction of compressor rotation is reversed for the purpose of defrosting the evaporator.

55 Figure 7 is a diagrammatic representation of another modification using solenoid valves.

Figure 8 is an enlarged detail of a spring stop seen in Figure 1.

The cabinet seen in the sectional view, Fig. 1, is ordinarily of a length considerably greater than the front to back horizontal dimension seen in this figure. The total height of the cabinet may be 6 or 8 feet, its depth from front to back 2 or 3 feet and its length varied according to the storage capacity desired. Various models might be from 4 to 10 feet long. These typical dimensions are mentioned as an aid to the explanation of the usage of the cabinet. The dimensions and proportions may vary considerably to fit special products or locations.

The cabinet 10 is designed to be placed with its back (right side of Figure 1) against a wall, or a pair of cabinets may be placed back to back. In any event the front opening 12 is next to the aisle so that customers can reach through this opening into the refrigerated space 14 to remove a package 16, 18, or 20 as desired. When one of these packages is removed, a similar package is pushed into view by the action of gravity upon packages stored in the corresponding vertical chute or magazine 26, 28 or 30.

The mirrors 34 and 36 are mounted at suitable angles for reflection of the images of the packages which are visible in the space 14 so that customers at some distance from the cabinet can see true reflections in the mirror 34 and, assuming the packages to be properly placed in the cabinet, can read the labels on the packages in the mirror 34 whereas images seen in a single mirror, not using this double reflection principle, are reversed. As the customer walks toward the cabinet the changing angles of reflection will cause a shifting of the images until she can look directly into the space 14 at the visible packages 16, 18 and 20. There will, of course, be a large number of packages visible within the space 14 due to the length of the cabinet. In a cabinet having an overall length of 8 feet, there may be 10 or more sets of chutes 26, 28 and 30 providing for the display of 30 or more packages in the space 14.

At a higher level on the front of the cabinet, there is a frame and sign-supporting device 40 for display of advertising signs, price cards, etc., preferably of a removable nature so that they can be changed to match the products displayed in the cabinet. Another sign and price card holder is shown at 42 and may be either a permanent sign or a frame designed to support changeable signs as desired. This lower sign holder 42 is primarily a door hinged at 44 to the cabinet 10 so that it may be swung through an arc of 270° to the position 42' indicated by dotted lines. In this position the door 42 closes the opening 12 in a substantially airtight manner by making contact with the rubber gaskets 46 and 48. In this position the door 42' serves as a running board or platform upon which merchandise can be stacked and the attendant can stand when refilling the cabinet.

The side of the door 42 which is hidden during the day and is uppermost when the door is closed during the night may be provided with a tread 50 (50' in the dotted position). The door 42 is to be insulated to minimize heat leakage during the night and may if desired be made thicker than shown to provide more insulation, though the heat leakage at the opening 12 is minimized by other means which produce stratification of air and retard its circulation in the space 14, thus it is not necessary that the door

42 be as heavily insulated as the main walls of the cabinet.

Below the door 42 in its open position is a rail or ledge 52 which may be used as a step to aid in mounting the running board. The hinge 54 of the door 56 is also designed to serve as a step for the attendant who refills the cabinet.

The proportions of these parts and of the cabinet itself are preferably such that the attendant 10 will be virtually forced to close the door 42 before opening the top door 60 of the cabinet. Very little of the rail 52 should extend beyond the door 42 when the door is in its open position. The door 56 is opened only occasionally for access to the condensing unit and when thus opened rests in the position 56' shown by dotted lines.

The feature of discouraging the improper opening of the door 60 while the door 42 remains open is to prevent the excess spillage of cold air which would result from this practice. The door 60 is fitted around its outer edge with a gasket 62 which seals the outer metal covering of the door to the liner 63 which is preferably made of non-conducting material. The cabinet 25 is fitted with an additional gasket 64 which makes contact with the door 60. This gasket seals the lining of the cabinet to the insulating breaker strip or frame 65. The use of two gaskets is to minimize and substantially eliminate air leakage into the cabinet when the door 60 is closed.

The flap 58 is a curtain of flexible material designed to contact the packages 16 and retard air flow between the chute 26 and the space 14. Additional flaps of this material may be employed at the sides of packages and at the delivery ends of the other chutes, but the one shown at 58 is the most important since it is nearest to the opening 12 and acts to retard the flow of cold air from the chutes 26 to the opening 12.

The finned evaporator 66 is supported by hangers 67 from the door 60 and extends substantially the full length of the upper space 68 above the chutes which hold the frozen food packages. This evaporator may be formed of tubes passing through sheet metal fins or it may be of the sheet metal or "plate" type and may be provided with headers in any preferred manner, but it is desirable that the evaporator be arranged to drain liquid downwardly and toward the door 60 when in the position 66' which it assumes when the door 60 is opened to the position 60'.

During business hours of normal usage of the cabinet, the door 60 remains closed and the door 42 remains open. The evaporator 66 is operated at a temperature considerably below freezing and preferably well below 0° F. This cools the air in the space 68 and this cold air drops into the several chutes 26, 28 and 30. There will be some thermal circulation of air within the chutes and a more pronounced thermal circulation of air in the space 68 but it is preferred that this circulation be quite slow.

Due to the height from the opening 12 to the upper door 60, there will be a tendency for the air in the chutes 26, 28 and 30 to flow through the space 14 and spill out of the opening 12, but this gravitational movement of cold air is minimized by the use of the double gaskets 62 and 64. The result will be a slight reduction of atmospheric pressure in the space 68 and substantially no upward flow of cold air through the

space 14, but air currents within the room will cause some circulation of air through the opening 12. In order to minimize this loss of refrigeration due to circulation of room air the end walls of the cabinet 10 are provided with wings 70 which need not be heavily insulated and may omit insulation entirely. These wings may be continuations of the outer metal sheathing of the two ends of the cabinet and their inner faces may be mirrors so that a person approaching the cabinet from one end will see the food display mirrored in the opposite wing 70.

The condensing unit 72 comprises a motor-compressor unit 14, a condenser 76 and a fan 78 mounted on a common base, the whole being removable through the front of the cabinet by opening the door 56 and disconnecting the tubes and wires at points which are accessible through its opening. The motor-compressor unit 14 is indicated as a sealed unit of horizontal type because it is desirable to keep the overall height of the condensing unit 72 as low as possible, but any suitable types of motor and compressor may be used. The liquid tube 80 and the suction tube 82 are preferably in heat exchange with each other within the conduit 84 which extends up the back of the cabinet. The upper end of the liquid tube 80, above the heat exchange section, is connected with the restrictor tube 86 or with an equivalent liquid control device, but in any event there is a section of liquid tube 86 of sufficient length and flexibility to permit opening of the door 80 without undue bending stress which might in time cause this tube to break.

When the door 60 is in its normal closed position (seen in Fig. 1) the liquid refrigerant flow from the restrictor tube 86 is directly to the inlet tube 88 of the evaporator 66. Refrigerant vapor leaves the evaporator through the tube 90 which normally leads directly to the coiled tube 92. Since the suction tube must be of larger diameter than the liquid tube 86 and must also be flexible, it is coiled in several turns around the hinge pin 94. The tubes 82 and 80 are preferably connected with the flexible tubes 92 and 86 by means of unions so that the door 60 and parts mounted thereon can be completely assembled as a unit and then mounted on a cabinet. This also provides for removal of the door assembly for servicing. In order to provide for this coil 92 surrounding the hinge pin, the pin is located farther from the body of the door 60 than would otherwise be required, but to minimize the requirement for clearance back of the cabinet when the door 60 is open, the hinge pin 94 is located somewhat above the plane of contact between the door 60 and the cabinet 10.

The coiled suction tube 92 connects with the suction tube 82 extending downwardly within the conduit 84 to the compressor 14 which discharges compressed refrigerant through the tube 96 to the condenser 76, thus completing the normal circuit of the system as employed in cooling the cabinet.

Since this cabinet is to be held at temperatures considerably below freezing, the controls of the system will necessarily be set to prevent any defrosting of the evaporator or of the product stored within the cabinet during normal operation, thus frost must necessarily build up on the evaporator 66. The amount of frost collected is minimized by the fact that infiltration of air is substantially prevented while the door

60 is closed. There will, however, be some slight leakage of air past the double gaskets 62 and 64. The air thus leaking into the cabinet will be lighter than the air already within the space 5 68 because it is warmer and because it will carry a much higher water vapor content than the cold air within the cabinet. The location of the evaporator 66, its shape, the shape of the baffle 98 and this fact of the incoming air being lighter 10 will insure that the air leaking into the cabinet makes contact with the evaporator 66 before it can make contact with the walls of the chutes 26, 28 and 30 or with any of the packages 16, 18 and 20.

15 The temperature of the evaporator 66 is to be maintained lower than the temperature of the packages and the rate of air flow over the evaporator and its extended surfaces is slow enough to insure that the absolute humidity of air in 20 the space 68 is maintained at a value low enough to prevent condensation of moisture from this air in the form of frost upon the packages or upon the walls of the chutes containing them when this air falls from the space 68 into the 25 chutes.

As seen in Figures 1 and 2, the baffle 98 is formed to provide a trough which will hold a small amount of water of condensation which will collect from the evaporator 66 during the 30 brief pull-down period when the system is first started up or after the evaporator has been defrosted. The evaporator 66 may have fins rounded at the lower front corners and inclined on their bottom edges for the purpose of directing drip into this trough, but such drip collection is limited to a very short period while the evaporator is being pulled down to its operating temperature.

40 Idle periods of the system will not be long enough to allow any defrosting of the evaporator 66 while the door 60 is closed, hence there will be no accumulation of condensate in the trough of baffle 98 and the small amount of water in it will be in the form of ice.

45 This baffle is designed specifically for performing a drainage function when the door 60 is open, as seen in Figure 2. While the baffle is perforated with numerous openings 100 for flow of air to the evaporator when the lid 60 is closed, these openings are so located relative to tubes and fins of evaporator 66 and so surrounded by up-turned edges that water dripping from the evaporator 66 while the door is open, as seen in Figure 2, will be conveyed to one or more pockets or troughs 50 102 from which water will drain through the tube or tubes 104 into the funnel 106 from which water drains through the tube 108 into container 110 which is mounted adjacent to or actually upon the condenser 76.

60 This drip trough or container will be designed to hold more water than is normally obtained from completely defrosting the evaporator after the maximum permissible collection of frost thereon. Between defrostings, the drip water 65 will be evaporated from the container 110 by means of heat from the condenser 76 and air moved by the fan 78. To facilitate this action, a piece of fabric 112 extends downwardly inside of the trough 110 to near its bottom and down the outside of the trough where air circulated by the fan will flow over it. This will easily provide for evaporating all of the water which can be collected from a single defrosting in less time than that of a normal period between defrostings.

70 In order to expedite defrosting of the evap-

operator 66 when the door 60 is open provisions are made for insuring that the condensing unit stops operation with respect to the cooling of evaporator 66 and means is provided for supplying heat to the evaporator 66 while the door is open. One method of doing this is illustrated by Figures 3 and 4, 4A and 4B. In Figure 3 the thermostatic switch 120 is connected in series with the motor of the motor-compressor unit 74 as usual but there is also in series with switch 120 a gravity-operated switch 124, which is here shown as being of the mercury type. In the position shown in Figure 3, the switch 124 closes the connection between the line wire 126 and the wire 128 which leads to a terminal of the thermostatic switch 120, the circuit through the motor being completed by the wire 130 and wire 132 which leads back to the line, assuming the switch 120 to be closed.

A suitable bulb connected with switch 120 is located in contact with 90 or at some suitable point within the refrigerated space and the mercury switch 124 is mounted on or within the door 60 so that it is tilted thereby when the door is opened. Assuming now that the mercury switch 124 as seen in Figure 3 is tilted 90° to the right, as would be caused by opening the door 60, it will be seen that the mercury will flow to the opposite end of the tube, breaking contact between 126 and 128 which will stop the motor in the event that it is running or prevent its starting in the event it is idle. The mercury in flowing to the opposite end of the tube makes contact between the line 126 and the wire 136 which leads to a resistance heating element 138 having its opposite end connected with the wire 140 which connects with the opposite side of the line, thus putting the heating element directly across the line while the motor of the condensing unit is definitely cut off.

The heating element 138 is protected by insulation 142, which may be of material on the order of mica, but is thermally associated with the coil of tubing 144 which acts as the evaporator of a secondary refrigerant circuit while the door 60 is open. Referring to Figure 4 in which the evaporator 66' is represented diagrammatically to show drainage of liquid therefrom into the tube 88 which was the inlet for liquid flow to the evaporator while the lid was closed, the tube 88 leads into a fitting 150 which includes a ball check valve 152. This ball closes the connection with the capillary tube 86 so that liquid flowing from the evaporator 66' will be diverted to flow downwardly through the tube 154 to the coil 144 which has an outlet end 156 leading to the fitting 158 within which there is a ball check valve 160 normally closing the now open port 162 which connects with the tube 164 leading to a fitting 166 within which there is a third ball check valve 168 now closing the end of tube 92 while allowing vapor to flow from tube 164 into the tube 90 which leads to the upper portion of the evaporator 66' which is no longer serving as an evaporator in this position. This completes a secondary refrigerant circuit which operates as follow:

When the door 60 is opened the circuit to the compressor motor is broken and the circuit to the heating element 138 is closed and in addition to this the check valve 152 has closed the port through which liquid refrigerant normally enters the evaporator and check valve 168 has closed the port through which refrigerant vapor normally leaves the evaporator. This isolates the evaporator from the high pressure side of the system and at the same time the ball check valve 160 opens the port 162 so that the evaporator 66 is in

open communication with the coil 144 which is now located at a lower level than evaporator 66, indicated by 66' in Figure 4.

The result is a reversal of function of the evaporator 66 which now serves as a condenser for refrigerant vapor produced by the electrical heating of the coil 144 and the drainage of liquid from 66' which now serves as a condenser. Since heat is applied to the coil 144 rapidly enough to cause defrosting of 66' within a short period of time, the pressure within the secondary refrigerant circuit which includes 66' may be higher than the pressure in the tube 80 or tube 92. If at the start of the defrosting operation some liquid flows from tube 86 into the fitting 150, it will not flow into the evaporator 66 but will flow through the tube 154 into the secondary evaporator 144.

The cover plate 174 is removably gasketed to the outer wall of the door 60 to provide access to the connections seen in Figure 4 and to the switches 120 and 124 for the purpose of servicing. This cover also provides gasketed outlets for the tubes 86 and 92 as well as for electrical leads connected with the heating element 138 and the switches which are located within the door.

It will be seen by reference to Figure 1 or by reference to Figure 4 rotated 90° to the left that during normal operation with the door closed the ports closed by check valves 152 and 168 will be open while the port 162 is closed by the check valve 160.

Refrigerant liquid entering the fitting 150 through the capillary tube 86 is prevented from flowing upwardly through the tube 154 by the fact that this tube has its outlet closed and because the coil 144 will be filled with warmer vapor. There is, therefore, no circulation of refrigerant through the tubes 154, 144, 156 and 164 when the door 60 is closed. Likewise there is no heat applied to the coil 138 while the door is closed as the circuit is broken at mercury switch 124.

Figure 5 is an enlarged detail of the top forward portion of the cabinet showing how the liner 63 of the top door and the breaker strip or frame 65 at the top opening of the cabinet are attached to the outer metal pan of the door and the liner of the cabinet respectively using the gaskets 62 and 64 which are designed both for sealing the door opening when the door is closed and for sealing the joint between the door liner and the outer metal covering of the door and for sealing the breaker frame to the cabinet liner.

Figure 6 shows the wiring diagram used in the event that it is desired to defrost the evaporator by reversing the pumping action of the compressor instead of by isolating the evaporator and using the electrical heating element 138. This method eliminates the need for the valves 150, 158 and 166. With this arrangement the mercury switch 124 shorts out the thermostat and closes a circuit through the wire 180 to cause the motor-compressor unit 74 to rotate in the reverse direction. This assumes the use of a rotary compressor of a type which reverses the direction of its pumping action when its direction of rotation is reversed. The result is that refrigerant vapor is discharged under high pressure into the evaporator 66' which now acts as a condenser and refrigerant liquid flows in the reverse direction through the capillary tube downward to the condenser 76 which now acts as an evaporator.

Figure 7 illustrates a further modification in which the defrosting is accomplished by operating the motor-compressor unit in its normal di-

rection of rotation, but reversing the flow of refrigerant to produce the same result as that obtained in Figure 6. The wire 182 connects with mercury switch 124 so that current flows in series through a pair of solenoids and the wire 184 to the motor of unit 74. The solenoid 186 acts to lift the suction valve 187 and the solenoid 188 acts to lift the discharge valve 189. When these two valves are lifted as a result of the top door 60 being opened the compressor discharges high pressure refrigerant vapor to the evaporator 66' which now acts as the condenser and refrigerant vapor is withdrawn from the condenser 76 which now acts as an evaporator. In either of these two reverse cycle hook-ups the refrigerating system acts in reverse to transfer heat from the room to the evaporator 66' for the purpose of defrosting it.

Using either of these reverse cycle systems or the electrically heated secondary system best illustrated by Figure 4 will provide for defrosting the evaporator 66 (66') by making it act as a condenser while the door 60 is open. In any one of these three systems, it may be considered advisable to provide automatic means for limiting the defrosting period in the event that the door is left open for a longer period than is required to melt all of the frost from the evaporator. Such means is easily provided by a thermostatic or pressure operated switch connected in the heating circuit or in the reverse motor circuit and arranged to open in response to the rise of pressure in the evaporator 66' or of temperature of the evaporator 66' to a point high enough to insure that all frost has been melted from the evaporator, any extended surface thereof and from the baffle 98.

The check valves 152, 160 and 168, Figure 4, may be dispensed with by connecting the tubes 86 and 92 so that liquid does not flow downwardly in either of them by gravity when the door 60 is open. It is only necessary that liquid flowing from the evaporator 66' flows into the coil 144 and not into the tube 86 and that vapor leaving the coil 144 flows to the evaporator 66'. Normally there will be some flow of vapor through the tube 92 during a defrosting period as shown by Figure 4 if the check valve 168 is omitted, thus building up some vapor pressure in the compressor housing. Likewise there will be some flow of vapor through the tubes 86 and 88 into the condenser 76. Such transfer of refrigerant vapor will reduce the charge of refrigerant available for defrosting the evaporator 66' of Figure 4 but not to the extent of preventing the defrosting. Since the compressor and condenser will always be well above 32° F., there will be no condensation of refrigerant vapor except in the colder portions of the evaporator 66'. After all of the frost has been melted from the evaporator 66', there will be more transfer of refrigerant to the compressor housing and to the condenser but this occurs after the defrosting operation is completed.

The door 60 or its hinges will be provided with suitable balancing or latching means to hold the door in its open position without requiring that the door be tilted too far beyond its vertical position. It is desirable that hardware of this type be used so that it is not necessary to open the door more than 90° as such wider opening to reach a balancing point would require additional space back of the cabinet which will often be placed with its back against a wall of the room.

The coiled portion of tube 92 which provides flexibility for door movement will normally be

wound so that when not stressed in either direction it will represent the position it assumes when the door is 45° open; thus the amount of flexibility required is 45° of movement in each direction from this half-way point. There are various types of flexible tubing made of metals and plastics which could be used in place of the plain coiled tube shown. It is also possible to make the connection through a movable joint associated with a hinge and this joint may also serve as a valve to isolate the evaporator 66' and the coil 144 from the balance of the system when the door is opened. Another use for such a hinge type valve would be to utilize it to perform the functions of the valves 187 and 189 shown in Figure 7.

The drain tube 104 seen in Figure 2 is preferably formed so that when the lid 60 is closed it forms a trap for water at a point far enough from the inside of door 60 and from cold parts of the refrigerating system so that water does not freeze in this trap but serves only as a seal to prevent air circulation. This trap is formed so that it also retains enough water at the end of each defrosting period while the lid is in its open position 60' to provide a water seal of sufficient depth to prevent ambient air from entering the refrigerated space through the tube 104 when the lid 60 is closed. As previously explained, the air pressure at the top of space 68 will be less than that of room air due to the weight of the column of cold air in this space and in the chutes above the level of the opening 12. Trapped water seals the tube 104 against this slight pressure difference.

A number of diagonal broken lines leading from 192 at the left of Figure 1 indicate angles of reflection as seen by a human eye at position 192. It will be noted that when the customer's eye is in this position packages 16 and 18 are directly visible, package 20 is visible by reflection in mirror 34 and package 18 is visible by double reflection in mirrors 34 and 36. The reflected images which the customer sees in mirror 34 first as the cabinet is approached thus provide a moving effect. The lettering on packages seen by double reflection is directly readable and when the customer approaches the cabinet closely the lowermost package in each chute is directly visible.

While I have shown the evaporator 66 and the baffle 98 movably mounted as a unit with the door 60 and the evaporator moving to a position entirely outside of the refrigerated space, it will be understood that some of the objects of my invention may be attained by moving only the evaporator or by moving only the baffle or drip pan. The evaporator may lift or slide instead of being hinged or the evaporator may remain stationary while the baffle or pan isolates it from the stored product so that the defrosting can occur without undue rise of temperature of the frozen foods.

Packages stored in this refrigerator will collect much less frost than usual because of the fact that all inward leakage is at the top and incoming air has its dew point lowered by the evaporator 66 before it contacts the packages in the chutes. In addition defrost water is prevented from touching the packages so that ice does not form on them. Any tendency of the packages to freeze together will be the result of frost collected on them prior to placing them in the cabinet. This frost will not form an ice bond between the packages if the cabinet temperature is properly maintained, but in the event that there is a tendency for the packages to freeze together in the

chutes they will be broken apart when passing through the curved portion of any one of the chutes.

For inventory purposes the number of packages in each chute can be calculated by measuring the distance from the uppermost package to the top of the cabinet. An approximate indication of the number of packages in each chute is provided by means of the spring stop 194 which is indicated in Figure 1 and shown enlarged in Figure 8. This spring stop provides a cushion effect when packages are dropped into an empty chute and the amount of spring deflection is an approximate measure of the weight of the packages in the chute. During business hours an attendant may observe the positions of these spring stops to determine whether or not any of the chutes are nearly empty, thus avoiding the necessity for opening the top door 60 unnecessarily. It may sometimes be desirable to open the door 60 for a short period to refill one or more chutes without defrosting the evaporator. This is easily provided for by placing a manual switch in the line 140 of Figure 3, 182 of Figure 5 or 180 of Figure 6 according to the type of defrosting arrangement employed.

As will be seen in Figure 1, the width of the opening 12 may be considerably less than the width of the display represented by the packages 16, 18 and 20. This opening need only be wide enough for the convenience of the customer in reaching the packages and may be even narrower than indicated in the drawing. The gasket 46 or the reflector above the lamp 49 may narrow the opening further. Mirrors 34 and 36 may be flat as shown or curved to enhance or modify the display by reflection. This double reflection which makes labels readable before the observer comes close enough to the cabinet to actually look down into the space 14 makes it practical to reduce the width of the opening 12 and thus reduce loss of refrigeration due to air flow and radiant heat transfer.

The use of the curved chutes allows the outer wall of the cabinet to be curved at the bottom above the condenser 76 as seen in Figure 1. This curvature greatly facilitates air flow over the condenser, making it possible to omit the fan 78 and depend upon thermal circulation of air if the designer prefers such an arrangement.

The drain tube 104 is shown in Figure 2 only, but it will be understood that the section seen in Figure 2 is very close to the section seen in Figure 4 and the tube 104 may be in heat exchange with the tube 86 and the tube 156. The object of such heat exchange is to insure against freezing of water in the tube 104 during either the operating period with the door 60 closed or the defrosting period with the door in the position of 60'.

During operation of the system to cool the cabinet the tube 104 is heated by liquid refrigerant flowing through the tube 86. During the defrosting operation the tube 104 is heated by the hot vapor flowing through the tube 156.

The thermostatic control indicated at 120 in various drawings may have a bulb associated with the suction tube 90 or it may be responsive to the temperature of the evaporator 66 or to the temperature of air adjacent to this evaporator. It may be a switch of the so-called "low pressure" type which is actuated directly by the pressure of refrigerant vapor leaving the evaporator. In any of these cases the switch 120 will close during the defrosting operation if it was open at the time defrosting started. This insures that when the

lid 60 is closed at the end of the defrosting period the evaporator 66 will immediately start cooling the cabinet.

I claim:

- 5 1. In a refrigerator, a food storage space, a refrigerating system including an evaporator for cooling said space, a door for access to said space, and means activated by the opening of said door for causing said evaporator to act as the condenser of said system for the purpose of defrosting it.
- 15 2. A refrigerator including a storage space, a refrigeration system including an evaporator operated at below 32° F. to cool said space, means for defrosting said evaporator, and means for collecting the defrost water which drips from said evaporator, said collecting means serving during normal operation of said system as a baffle to direct air flow within the refrigerator.
- 25 3. In a refrigerator, a food storage space, an upper door providing access to said space for loading it, a hinged lower door providing access to said space for removal of articles inserted through the upper door, means facilitating the opening of said upper door, said means being effective only when said lower door is swung to its closed position, and a refrigerating system including a cooling element located adjacent to said upper door.
- 30 4. In a refrigerator cabinet, a refrigerating system, a door, a cooling element of said system mounted on the inner side of said door, heating means for defrosting said cooling element, drip collecting means, and means actuated by the opening of said door to energize said heating means to initiate a defrosting period of said cooling element and to move said drip collecting means into position to receive the drip from said cooling element.
- 35 5. In a refrigerator cabinet, an evaporator of a refrigerating system arranged to cool said cabinet, means for stopping said cooling, and means for causing said evaporator to act as the condenser of a one pressure evaporative heat transfer system for the purpose of defrosting said evaporator.
- 40 6. In a refrigerator cabinet, an evaporator for cooling said cabinet, a door for said cabinet, and valve means actuated by movement of said door, said valve means serving to control the defrosting of said evaporator.
- 45 7. A refrigerator cabinet, a refrigerating system including an evaporator arranged to cool a space within said cabinet by the evaporation of a volatile refrigerant, means for isolating said evaporator from said space, and means actuated simultaneously with the first said means for causing said evaporator to operate temporarily as a condenser for the purpose of defrosting it by condensing said volatile refrigerant therein while the temperature of said space remains substantially constant.
- 50 8. A refrigerator, a storage space within said refrigerator, a refrigerating system, an evaporator of said system located within said space, said system including a compressor of a type adapted to reverse its direction of pumping action when its direction of rotation is reversed, means for reversing the direction of rotation of said compressor to cause said evaporator to be defrosted by functioning temporarily as a condenser, and means for modifying the normal relationship of said evaporator to said space during its period of operation as a condenser so that it dissipates

- 60
- 65
- 70
- 75

heat to ambient air and drains defrost water outside of said space during its defrosting period.

9. In a refrigerator, a space for the storage of products to be cooled, an evaporator for cooling said space, a movable baffle element within said space, said element being movable to a second position in which it serves as a drip collecting means adapted to receive defrost water as it drips from said evaporator, and means made effective upon movement of said element to its drip collecting position for causing said evaporator to defrost.

10. In a refrigerator, a space for storage of products to be maintained at a low temperature, an evaporator for cooling said space, means for cooling said evaporator by supplying a volatile refrigerant to it and removing vaporized refrigerant therefrom, a normally by-passed heat exchanger, means for heating said evaporator by evaporating a volatile refrigerant in said heat exchanger and causing it to condense in said evaporator for the purpose of defrosting it, and switch means operable to connect either of the first two means with a source of electrical energy, said switch means operating to cut off the electrical energy supply to either of the first two means before closing the circuit which energizes the other.

11. In a refrigerated cabinet, a chamber for storage of frozen foods, a plurality of chutes in said chamber adapted to hold said foods, an evaporator located within said chamber for cooling air therein, an upper door for said chamber adjacent said evaporator, a second door opening into said chamber at a lower level, said evaporator being adapted to operate at a temperature far enough below the freezing point of water and so located with relation to said upper door that any air leaking into the cabinet around said door will be cooled by said evaporator to the extent of having its dew point reduced to a temperature below that of the food in storage in said cabinet before said air comes in contact with said food or with packages containing the food.

12. A refrigerator having a door and enclosing a storage space for frozen foods, a refrigerating system for cooling said space to a sub-freezing temperature, a cooling element forming a part of said system, and means for applying heat to said cooling element to defrost it, said means being energized by the opening of said door, means for collecting drip water from said cooling element while it is being defrosted, the last said means including a drip trough normally located within said storage space and moved to its defrosting position by said door, and means for conducting said drip water to a disposal point, said collecting means, conducting means and disposal point being located entirely outside of said storage space during the defrosting operation.

13. In a refrigerator, a space for storage of foods, a refrigerant evaporator for cooling said space, a door for closing said space, means responsive to the opening of said door to apply artificial heat to said refrigerant evaporator, a drip water evaporator, and means actuated by said door as it is moved to its open position to provide for catching defrost water from said refrigerant evaporator and draining it to said drip water evaporator.

14. In a refrigerator cabinet, a space within said cabinet for storage of a product to be refrigerated, a door opening for access to said space, a door for closing said opening, a refrigerating system including an evaporator arranged to cool said space by the evaporation of a volatile re-

frigerant therein, valve means for changing the direction of flow of said refrigerant through a part of said system and thereby causing said evaporator to function temporarily as a condenser for the purpose of defrosting it, and means actuated by a movement of said door for operating said valve means.

15. The method of defrosting an evaporator of a refrigerating system by a single movement which shuts it off from other parts of the system and causes it to operate temporarily as the condenser of a single pressure volatile fluid heat transfer system with condensed fluid draining to a lower level, being reevaporated by the application of heat and returning as vapor to heat the evaporator which is temporarily acting as a condenser.

16. In a refrigerating system employing a volatile refrigerant, a high side section including a condenser, a low side section including an evaporator, and a normally inactive heat exchange section, means for causing liquid refrigerant to drain from said evaporator into said heat exchange section, means becoming effective simultaneously with said draining means for applying heat to said heat exchange section to cause said liquid to evaporate therein, and means for conveying vapor from said section directly to said evaporator with no change of pressure for the purpose of causing the evaporator to operate temporarily as a condenser and thereby be defrosted.

17. In a refrigerator cabinet, a space for storage of a product to be cooled, a refrigerating system including an evaporator arranged to cool said space, means for defrosting said evaporator by applying artificial heat thereto, a door on said cabinet, and control means actuated by a movement of said door, said control means being connected with said system and with said defrosting means so that one movement of said door stops the cooling operation of said evaporator and starts its defrosting while an opposite movement of said door stops the defrosting and causes the cooling to start again.

18. In a refrigerator cabinet, a space for the storage of products to be cooled, closure means for said space, a refrigerating system including an evaporator for cooling said space by the evaporation of a volatile refrigerant, means for reversing the action of said evaporator so that refrigerant condenses therein to defrost it, and a drip evaporator, said reversing means being actuated in response to a relative movement between said evaporator and space, said movement also acting to provide a non-refrigerated path for carrying drip water from the first said evaporator to the drip evaporator.

19. In a refrigerating system, an evaporator section including an evaporator and a normally by-passed heat exchanger, a refrigerant condensing section including a condenser, a volatile refrigerant enclosed within said system and normally circulating therein to vaporize in said evaporator and liquefy in said condenser, means for stopping the circulation of said refrigerant between said sections, and electrical means for heating a portion of said refrigerant which is in its liquid phase in said heat exchanger to evaporate it and thereby cause it to condense in said evaporator for the purpose of defrosting the evaporator.

20. In a refrigerator cabinet of the type adapted for cooling a product in its original containers, a delivery opening for said containers, multiple chute means for guiding the movement

of said containers toward said delivery opening, and means responsive to changes in the total weight of the containers in one of said chutes for indicating at least approximately the number of containers remaining in that chute, said chutes being refillable at one end and adapted to deliver containers at the other end so that a container which has been in a given one of said chutes for the longest time will be the next one delivered therefrom.

21. A refrigerated cabinet adapted for the storage of frozen foods, a compartment for the storage of frozen foods having a pair of access openings, one of said openings being at a higher level for the introduction of packages to said compartment, another of said openings being at a lower level for the removal of packages from said compartment, a tightly fitting operable closure for said higher opening, an evaporator carried by said closure and positioned within said compartment for cooling the air therein, said evaporator being closely adjacent said upper opening whereby any air leaking into said compartment will be cooled by said evaporator to a temperature below that of said packages whereby its dew point is reduced below said package temperature before said air comes in contact with said packages, an openable closure for said lower opening, and means dependent upon the placing of said second-named closure in a position to close said lower opening for facilitating the opening of said first-named closure whereby the user is impelled to close said lower opening before opening said upper opening.

22. A refrigerated cabinet adapted for the storage of frozen foods, a compartment for the storage of frozen foods having a pair of access openings, one of said openings being at a high level for the introduction of packages to said compartment, another of said openings being at a lower level for the removal of packages from said compartment, a tightly fitting hinged closure for said higher opening, an evaporator adapted to be cooled below the freezing point of water carried by said closure and positioned within said compartment for cooling the air therein, said evaporator being closely adjacent said upper opening whereby any air leaking into said compartment will be cooled by said evaporator to a temperature below that of said packages whereby its dew point is reduced below said package temperature and the excess moisture condensed out in a frozen form on said evaporator before said air comes in contact with said packages, means for causing said condensed moisture to melt from said evaporator as a consequence of the opening of said closure, means rendered effective upon the opening of said closure for collecting the moisture melting from said evaporator whereby it is prevented from coming in contact with said packages, a hinged closure for said lower opening, and means dependent upon the placing of said second-named closure in closed position for facilitating the opening of said first-named closure whereby

the user is impelled to close said lower opening before opening said upper opening.

23. In a refrigerator, a compartment adapted for the storage of frozen foods, a refrigerating system including an evaporator arranged to cool said compartment, means for isolating said evaporator from said compartment, means for shutting said evaporator off from connection with other parts of said system, means for heating said evaporator to defrost it, and control means for substantially simultaneously actuating two of the aforesaid means.

GLENN MUFFLY.
